UNITED STATES PATENT OFFICE.

LLOYD ESPENSCHIED, OF QUEENS, NEW YORK, ASSIGNOR TO AMERICAN TELEPHONE AND TELEGRAPH COMPANY, A CORPORATION OF NEW YORK.

MULTIPLEX SIGNALING CIRCUITS.

Application filed July 1, 1921. Serial No. 481,916.

To all whom it may concern:

Be it known that I, LLOYD ESPENSCHIED, residing at Queens, in the county of Queens and State of New York, have invented certain Improvements in Multiplex Signaling Circuits, of which the following is a specification.

This invention relates to signaling systems, and more particularly to signaling systems of the multiplex type.

Heretofore, in multiplex signaling circuits employing carrier currents for transmission over individual channels, it has been customary to select into the individual circuits corresponding to the channels of the multiplex system by simultaneously applying all of the frequencies corresponding to the different channels upon a selecting system for filtering individual frequencies into the proper channels. The separation into the different channels is accomplished directly at the frequencies of transmission, without the intervention of any frequency conversion process.

In accordance with the present invention, the selecting process is carried out in connection with the process of frequency conversion. In carrying out the process at the receiving portion of the system, several signaling bands are received upon a common circuit and the lowest band selected from the remaining bands for transmission to its proper channel. The remaining bands are then stepped down together, so that the next lowest band will occupy substantially the same frequency range as the band previously selected. This band is then selected from the bands above and transmitted to its channel. This process is continued until all of the signaling bands have been selected into the proper circuits. In accordance with this method, the terminal channel circuits are all designed to have the same cut-off characteristic and the received transmission band carrying the plurality of individual bands is stepped into the channels one at a time through a succession of frequency conversions. At the transmitting part of the system, the method constitutes superimposing the several bands by taking an individual band, stepping it up to a frequency just above the frequency range normally occupied by the second band, combining with the stepped up band a second band, stepping

the resultant combined band up to a frequency range just above that normally occupied by a third band, combining a third band with the stepped up bands, etc., for as many channels as are to be combined. This method possesses the advantage that the act of selecting each carrier channel to or from its individual terminal circuit is carried out always at a frequency which is most favorable to the selecting action, namely the lowest frequency channel of the carrier group.

The invention may now be more fully understood from the following description, when read in connection with the accompanying drawings, Figures 1 and 2 of which illustrate two different forms of circuit arrangements for carrying out the principles of the invention.

Referring to Fig. 1, ML designates a main transmission line over which carrier currents may be transmitted, and L_1 , L_2 and L_3 low frequency signaling lines. The line L_1 is balanced by a network N_1 and is associated with the transmitting channel TL_1 and receiving channel RL_1 through the usual hybrid coil 11. The transmitting channel TL_1 leads to the input side of a modulator M_1 , which may be of any well-known type, but as illustrated is a vacuum tube modulator. The receiving channel RL_1 leads from the output circuit of a demodulator or detector D_1 , which is also illustrated as a vacuum tube detector, although any well-known type of detector may be employed. Selective arrangements such as filters, are employed in the transmitting and receiving channels. In the case illustrated, it is assumed that the signaling band occupies a range from zero to 3,000 cycles, and, therefore, a low pass filter RF_1 and a low pass filter TF_1 are included in the receiving and transmitting channels, respectively, the upper cut-off frequency of the filters being in the neighborhood of 3,000 cycles. The modulator M_1 and the detector D_1 are each illustrated as being supplied with a carrier frequency of 3,000 cycles, although the particular frequency employed is immaterial, except that it should be at or above the upper limit of the low frequency signaling band.

The output side of the modulator M_1 is associated with the input side of a modulator M_2 through a circuit including a band

filter TF_2' arranged to transmit a band of frequencies between 3,000 and 6,000 cycles. The input side of the detector D_1 is similarly associated with the output side of a detector D_2 through a circuit including a band filter RF_2' having the same transmission limits. A second low frequency signaling circuit L_2 is balanced by a network N_2 and is associated with a transmitting channel TL_2 and a receiving channel RL_2 through a hybrid coil 12. Low pass filters TF_2 and RF_2 are included in these channels, the low pass filters being illustrated as having the same upper cut-off frequency as the low pass filters previously described, this limit being set upon the assumption that the low frequency signaling band to be transmitted from the line L_2 will be the same as that transmitted from the line L_1 . It is not essential that these limits should be used, however, the only requirement being that the low pass filters have their cut-off frequencies above the low frequency signaling band and below the stepped up band with which they are to be combined. The channel TL_2 leads to the input circuit of the modulator M_2 and the receiving channel RL_2 leads from the output side of the demodulator D_2 . The demodulator D_2 and modulator M_2 are also supplied with a carrier frequency which is illustrated as being of 3,000 cycles, although some discretion may be exercised in determining the carrier frequency.

The output circuit of the modulator M_2 leads to a common transmitting channel TL and the common receiving channel RL leads to the input circuit of the detector D_2 . The common circuits TL and RL are associated with the main line ML through a hybrid coil 10. High pass filters TF_3' and RF_3' are included in the common circuits TL and RL adjacent to the modulator M_2 and the detector D_2 , respectively. The lower cut-off point of these filters is indicated as being 3,000 cycles, although the frequency so employed will vary with circumstances.

The low frequency transmission line L_3 is balanced by a network N_3 and is associated by means of a hybrid coil 13 with a transmitting channel TL_3 and a receiving channel RL_3 . Low pass filters TF_3 and RF_3 , similar to those already described, are included in these channels. The circuit TL_3 is connected to the common transmitting circuit TL and the circuit RL_3 is connected with the common receiving circuit RL .

Further details of the apparatus will be understood from the description of the operation. In considering the operation, the columns of numbers placed above and below individual portions of the apparatus in the circuit indicate the frequencies involved at those particular points in the circuits, and these frequencies should be kept in mind

when reading the description of the operation, which is as follows:

The low frequency signaling band incoming from the line L_1 is transmitted into the channel TL_1 through the filter TF_1 to the input circuit of the modulator M_1 . Assuming that this band extends from zero to 3,000 cycles, it combines in the modulator M_1 with the carrier frequency of 3,000 cycles to produce upper and lower side bands and a frequency component corresponding to the carrier as indicated in the column immediately below the modulator M_1 . The upper side band will extend from 3,000 to 6,000 cycles, and by means of the filter TF_2' , the lower side band and, if desired, the carrier, may be suppressed. (See numbers included in the dotted rectangle of the column below the modulator M_1 .) The selected band from 3,000 to 6,000 cycles, being passed through the filter TF_2' , is combined with a low frequency band from the line L_2 , which is transmitted through the low pass filter TF_2 . This band may also occupy the range from zero to 3,000 cycles.

The complete band of frequencies to be impressed upon the modulator M_2 is indicated in the column just below the input side of said modulator. As illustrated, this complete band comprises two sub-bands, one numbered 1 and comprising frequencies from 3,000 to 6,000 cycles corresponding to the signal incoming from the line L_1 , and the other designated 2 and comprising frequencies from zero to 3,000 cycles, corresponding to signals incoming from the line L_2 . This band of frequencies now modulates with the carrier frequency of 3,000 cycles applied to the modulator M_2 to produce upper and lower side frequencies as well as a frequency corresponding to the carrier, as indicated in the column below the output side of the modulator M_2 . The portions of each band corresponding to the original sub-bands are indicated by the numerals 1 and 2. As the filter TF_3' in the output circuit of the modulator has its lower cut-off point at 3,000 cycles, the carrier frequency and the lower side band frequencies will be suppressed, and two sub-bands of 6,000 to 9,000 cycles and 3,000 to 6,000 cycles, respectively, corresponding to the signals from the lines L_1 and L_2 , will be transmitted to the common transmitting circuit TL .

A low frequency signaling band from the line L_3 will also pass into the transmitting channel TL_3 through the filter TF_3 and be combined in the circuit TL with the two sub-bands previously referred to. Consequently, frequencies from zero to 9,000 cycles will appear in the circuit TL and will be transmitted to the main line ML . These frequencies comprise sub-bands corresponding to the signals from the three low frequency transmission lines as indicated in the column below the circuit TL .

cated by the numbers in the column immediately below the common circuit TL_1 .

In receiving, assuming that an operation similar to that just described is proceeding at a distant transmitting station, frequencies from zero to 9,000 cycles incoming from the line ML_1 will be transmitted to the common receiving circuit RL_1 . These frequencies, as indicated by the column above the circuit RL_1 , comprise three sub-bands numbered 1, 2 and 3, corresponding to the three low frequency transmission circuits to which the signals they represent will ultimately be transmitted. The lower band from zero to 3,000 cycles will be passed by the low pass filter RF_3 into the channel RL_3 , being excluded from the detector D_3 by the high pass filter RF_3' . The signaling band passed by the filter RF_3 will be transmitted through the hybrid coil 13 to the line L_3 . As this band of frequencies is supposed to represent a signal in the low frequency state, no detecting operation is necessary with respect thereto.

The high pass filter RF_3 selects the two sub-bands numbered 1 and 2, and impresses these bands upon the input side of the detector D_2 , where they are modulated with the carrier frequency of 3,000 cycles to produce upper and lower side bands and carrier frequency component indicated in the column designated "Output D_2 ." As the filter RF_2 is a low pass filter, selecting frequencies from zero to 3,000 cycles, and the filter RF_2' is a band filter selecting frequencies from 3,000 to 6,000 cycles, frequencies above 6,000 cycles will be eliminated, as indicated by the frequencies included in the dotted rectangle in the column last referred to. The band of frequencies from zero to 3,000 cycles, designated by the numeral 2, corresponds to a low frequency signal for transmission to the line L_2 , and this band of frequencies, being selected by the filter RF_2 , is transmitted through the hybrid coil 12 to the low frequency line. The remaining band of 3,000 to 6,000 cycles is passed through the filter RF_1 and modulated with the frequency of 3,000 cycles in the demodulator D_1 to produce upper and lower side bands and carrier, as indicated by the column of figures marked "Output D_1 ." The low pass filter RF_1 selects the lower band which is transmitted through the hybrid coil 11 to the low frequency line.

The system as above described is limited to not more than three channels, where the same carrier frequency is employed throughout. This is for the reason that the carrier frequency lies within the range of the complete band transmitted from the main line ML_1 , so that when a fourth channel is employed, the band of frequencies from 9,000 to 12,000 cycles, which would then be involved in transmission over the main line ML_1 , would, in modulating with the carrier frequency of 3,000 cycles, produce a lower side band lying within the same range as the upper side band produced by the band extending from 3,000 to 6,000 cycles. Interference between the channels would consequently result. In order that more channels may be employed, it is necessary to adopt a slightly different principle for the additional channels. This principle involves using carrier frequencies for the additional modulators and detectors necessitated by the additional channels, which frequencies will be higher than the highest frequency of the total band involved at the additional modulating and demodulating points. The principle employed will be clear from Fig. 2, in which the apparatus associated with the lines L_1 , L_2 and L_3 will be identical with the corresponding apparatus in Fig. 1, with the exception that the filters RF_3' and TF_3' will be band filters having ranges from 3,000 to 9,000 cycles, instead of being high pass filters. This particular range is used for purposes of illustration, it being understood that the range will vary depending upon the number and width of signaling bands employed. The channels TL_3 and RL_3 , instead of being connected directly to the common transmitting and receiving channels TL_1 and RL_1 , are connected to the input side of the modulator M_3 and the output side of the demodulator D_3 , respectively. The output side of the modulator M_3 is connected to the input side of the modulator M_4 through a band filter TF_4' whose range is indicated as being from 3,000 to 12,000 cycles. Similarly, the input side of the detector D_3 is connected through a band filter RF_4' having the same frequency range, to the output side of the demodulator D_4 . A low frequency transmission line L_4 is balanced by a net work N_4 and is associated through a hybrid coil 14 with a transmitting channel TL_4 and a receiving channel RL_4 including low pass filters TF_4 and RF_4 , respectively. The channels TL_4 and RL_4 connect the line L_4 to the input side of the modulator M_4 and output side of the demodulator D_4 , respectively.

The output circuit of the modulator M_4 is connected to the common transmitting circuit TL_1 through a band filter TF_5' having a transmission range indicated as extending from 3,000 to 15,000 cycles. Similarly, the input circuit of the demodulator D_4 is connected with the common receiving channel RL_1 through a selecting filter RF_5' . This filter may be either a band filter similar to the filter TF_5' or it may be a high pass filter as indicated. A low frequency line L_5 is balanced by a network N_5 and is connected through a hybrid coil 15 with transmitting channel TL_5 and receiving channel RL_5 , these channels including low pass filters

4
 TF₅ and RF₅, respectively, and being connected directly to the common transmitting and receiving circuits TL and RL, respectively. If additional low frequency lines are to be included in the system, the receiving and transmitting channels of the line L₅ will be connected to additional demodulators and detectors.

10 The modulator M₃ and the detector D₃ are indicated as being supplied with a carrier frequency of 12,000 cycles, and similarly, the modulator M₄ and detector D₄ are indicated as being supplied with a carrier frequency of 15,000 cycles. These frequencies must exceed the upper limit of the impressed band by at least the width of next incoming signal band impressed upon each particular demodulator and detector. In the case of the modulator M₃, the band impressed upon the input circuit of the modulator extends from zero to 9,000 cycles, and by modulating with the carrier of 12,000 cycles, will produce an inverted lower side band extending from 3,000 to 12,000 cycles, so that the band of frequencies will be elevated in the frequency spectrum a sufficient amount to permit another signaling band to be inserted below the modulated band. The band of frequencies impressed upon the detector D₃ extends from 3,000 to 12,000 cycles, and by modulating with the carrier frequency of 12,000 cycles, an inverted lower side band will be produced extending from zero to 9,000 cycles. In this instance, the inversion of the lower side bands restores the frequencies to their normal relation as the input frequency band will be already inverted before being applied to the detector, as will be clear later. The lower side band of the detected side band will, therefore, represent the low frequency signal and may be selected directly to the low frequency line.

15 Similarly, in the case of the modulator M₄, the input band extends from zero to 12,000 cycles, and this band, in modulating with the carrier frequency of 15,000 cycles, will be stepped up to a range from 3,000 to 15,000 cycles to permit an additional frequency band to be inserted below the stepped-up band. Likewise the band impressed upon the detector D₄ extends from 3,000 to 15,000 cycles, and by modulating with the carrier of 15,000 cycles, this is stepped down into a range extending from zero up to 12,000 cycles, thereby permitting the direct selection of the lower frequencies of this band into a low frequency signaling circuit.

20 The principles of this form of the invention and the details of the apparatus will be more clearly understood from the description of the operation, which is as follows:

25 A low frequency signaling band extending from zero to 3,000 cycles incoming from the line L₁ is selected into the channel TL through the filter TF₁ and applied to the modulator M₁. The operation of successive modulations in combination with additional low frequency bands from the lines L₂ and L₃ is the same as described in connection with Fig. 1, so that a band is finally selected to be applied to the input circuit of the modulator M₃ which extends from zero to 9,000 cycles and includes three sub-bands numbered 1, 2, and 3, respectively, these sub-bands corresponding to the lines L₁, L₂ and L₃. This entire band of frequencies is then impressed upon the modulator M₃ and modulates with the carrier frequency of 12,000 cycles to produce the upper and lower side bands and carrier frequency component indicated by the column of figures designated "Output M₃". The filter TF₄' eliminates all frequencies above 12,000 cycles so that the upper side band is suppressed. The lower side band now extends from 3,000 to 12,000 cycles. It will be understood, however, that the frequencies in this band will be reversed with respect to the frequencies in the input band so that the position of the sub-bands numbered 1, 2 and 3 in the frequency spectrum will be reversed, and the band numbered 3, which on the input side of the modulator was the lowest band of the series, is now the highest band of the series. The individual frequencies in each of these sub-bands are also reversed in order, so that the highest frequency of the sub-band is now the lowest frequency of the sub-band, and vice versa. The lower side band of from 3,000 to 12,000 cycles selected by the filter TF₄' is combined with a signaling band from the line L₄, said signaling band extending, in the case illustrated, from zero to 3,000 cycles. The total band comprising the four sub-bands will now involve the limiting frequencies indicated in the column marked "Input M₄".

30 This range of frequencies, upon being applied to the modulator M₄, modulates with the carrier frequency of 15,000 cycles to produce upper and lower side bands as indicated in the column marked "Output M₄". The filter TF₅ suppresses all frequencies above 15,000 cycles so that only the lower side band remains. This lower side band includes four sub-bands whose relative positions in the spectrum have been reversed as regards the four sub-bands applied to the input circuit of the modulator. For example, the sub-band designated 4 is now the highest range of frequencies whereas before it was the lowest, and the sub-band numbered 3 which was the highest sub-band before modulation is now the lowest sub-band in the group. Sub-bands 1, 2 and 3 now have their individual frequencies reversed with respect to the input bands of the

modulator M_4 , but their individual frequencies are in the same relative order in the frequency spectrum as they originally occupied in the corresponding sub-bands applied to the input circuit of the modulator M_3 . The individual frequencies of these three sub-bands are consequently not inverted with respect to the corresponding frequencies transmitted from the low frequency lines. The individual frequencies of the four sub-bands, however, are inverted with respect to the component frequencies of the band incoming from the line L_4 .

The band of frequencies selected by the filter TF_5' which has been shifted in the frequency spectrum by 3,000 cycles, is now combined with a signaling band from the line L_5 , which, in the case illustrated, is assumed to extend from zero to 3,000 cycles and is passed through the filter TF_5 of the channel TL_3 so that a combined band including five sub-bands extending from zero to 15,000 cycles is finally transmitted to the main line ML . Of the five sub-bands transmitted, bands 1, 2, 3 and 4 have all been shifted in the frequency spectrum but the fifth band is unshifted. The component frequencies of bands 1, 2, 3 and 5, are not inverted, while the component frequencies of the fourth band are inverted with respect to the original frequencies incoming from the low frequency lines.

Assuming that a similar transmitting operation is taking place at a distant sending station, a similar range of frequencies comes in through the line ML and passes into the common receiving circuit RL . This range of frequencies extends from zero to 15,000 cycles and comprises five sub-bands having frequency limits as indicated in the column designated "From line". The fifth sub-band, comprising frequencies from zero to 3,000 cycles will be selected without demodulation by means of the low pass filter RF_5 and transmitted to the line L_5 . The remaining four sub-bands will be passed by the high pass filter to the input circuit of the detector D_4 . These frequencies, by demodulation with a carrier frequency of 15,000 cycles, produce in the output circuit of the detector D_4 upper and lower side bands and carrier component as indicated by the column of figures marked "Output D_4 ". Since the filters RF_4' and RF_4 discriminate against all frequencies above 12,000 cycles, the carrier component and the upper side band will be suppressed, leaving a lower side band having four sub-bands designated 1, 2, 3 and 4. It will be noted that of the four sub-bands impressed upon the demodulator, the frequencies in sub-bands 1, 2 and 3 are not inverted with respect to the signaling frequencies of the bands from which they originated, while the frequencies in the fourth sub-band are inverted with re-

spect to the original frequencies. The frequency in the individual sub-bands of the lower side band of the demodulator D_4 are inverted with respect to the input frequencies and the order of the bands in the frequency spectrum is also inverted. Consequently, the fourth sub-band which was the highest sub-band on the input side of the demodulator becomes the lowest sub-band in the output, and its frequency range is from zero to 3,000 cycles. Therefore, this band of frequencies will be selected by the filter RF_4 and will be transmitted directly to the line L_4 as a signal.

The remaining sub-bands fall within the limits of the filter RF_4' and are impressed upon the demodulator D_3 . By demodulation with the carrier frequency of 12,000 cycles supplied to the demodulator, the two side bands and carrier component indicated in the column designated "Output D_3 " will be suppressed. The filters RF_3 and RF_3' suppress all frequencies above 9,000 cycles. Consequently, the carrier component and the upper side band are eliminated. The three sub-bands making up the lower side band are again inverted in their order, and their frequencies are also inverted, with the consequence that the relative order of the frequencies in each band will correspond to the order of the frequencies in the original bands, and the bands will be arranged in the spectrum in the inverse numerical order of the bands. The band designated 3, which extends from zero to 3,000 cycles, will, therefore, be selected by the filter RF_3 and transmitted directly to the line L_3 as a signal, while the remaining two bands will be passed through the filter RF_3' to the detector D_2 . From this point the operation will be as described in connection with Fig. 1.

It will be understood that the frequencies hereinbefore referred to and indicated on the drawing have merely been given in order to clearly elucidate the principles of the invention, though in practice other frequencies than those given may be used. For example, the carrier frequency applied to the modulator M_1 and demodulator D_1 may be 6,000 cycles and the carrier frequency applied to the modulator M_2 and the demodulator D_2 may be 9,000 cycles. In this case, the band applied to the modulator M_1 will produce in the output circuit a lower side band from 3,000 to 6,000 cycles, which will be selected to the exclusion of the other side band by the filter TF_2' . This band will have added thereto a band extending from 3,000 cycles to zero from the circuit TL_2 and the two bands will be applied to the modulator M_1 in the output of which will appear a lower side band comprising sub-bands from 6,000 to 9,000 cycles and from 3,000 to 6,000 cycles, the former corresponding to the band from the channel TL_1 .

and the latter to the band from the channel TL_2 . The two sub-bands comprising the lower side band of the modulator M_2 will be selected by the filter TF_2' and from this point the operation will be same in the case of Fig. 2 as already described.

In a similar manner, the two sub-bands of 6,000 to 9,000 cycles and 3,000 to 6,000 impressed on the demodulator D_2 result in 10 the production of a lower side band in the output circuit of said demodulator, which side band comprises two sub-bands, one extending from zero to 3,000 cycles and the other extending from 3,000 to 6,000 cycles. 15 The former sub-band corresponds to sub-band No. 1 and the latter to sub-band No. 2. These two sub-bands will be selected to the exclusion of the frequencies in the upper side band and the sub-band No. 1 will be 20 selected by the filter RF_2' to be impressed upon the demodulator D_1 , the sub-band from zero to 3,000 being selected into the circuit RL_2 . The band from 3,000 to 6,000 cycles, when impressed upon the demodulator D_1 , 25 appears in the output circuit thereof as a lower side band extending from zero to 3,000 cycles, and said lower side band is selected into the circuit RL_1 . Various other obvious modifications in the frequencies employed 30 may also be used.

It will be obvious that the general principles herein disclosed may be embodied in many other organizations widely different from those illustrated without departing 35 from the spirit of the invention as defined in the following claims.

What is claimed is:

1. The method of signaling which consists in successively stepping up a signaling band in the frequency spectrum and combining the stepped-up band with an additional signaling band each time a stepping up operation occurs.

2. The method of signaling which consists in stepping up a signaling band in the frequency spectrum, combining with the stepped-up band another signaling band, stepping up both bands together, and combining with the resultant stepped-up band 50 another signaling band.

3. The method of signaling which consists in stepping up a signaling band in the frequency spectrum to a point above that occupied by another normal signaling band, 55 combining the stepped-up band with the said other normal signaling band, stepping up the resultant band to a point in the frequency spectrum above a third normal signaling band, and combining the stepped-up band with said third band.

4. The method of signaling which consists in stepping up in the frequency spectrum a normal signaling band, combining therewith another normal signaling band, 65 stepping the combined bands up in the fre-

quency spectrum, combining with the stepped-up bands an additional normal band, and continuing the process of stepping up and adding normal signaling bands for all of the signaling bands to be transmitted.

5. The method of signaling which consists in stepping up a normal signaling band to a point in the frequency spectrum above a second normal signaling band, combining 75 with the stepped-up band the second normal signaling band, stepping up the combined band to a point in the frequency spectrum above a third normal signaling band, combining the stepped-up bands with said third 80 normal signaling band, and continuing the process of stepping up bands and adding normal signaling bands for all of the normal signaling bands to be transmitted.

6. The method of signaling which consists 85 in modulating a normal signaling band with a carrier so chosen as to produce a side band corresponding to the original signaling band and occupying a frequency range above the original signaling band, selecting said side band to the exclusion of other frequencies, combining with the selected band another normal signaling band, modulating the combined bands with a carrier so chosen as to translate the combined bands to a point in 90 the frequency spectrum higher than a third normal signaling band, selecting the frequencies thus translated to the exclusion of other frequencies, and combining therewith said third normal signaling band.

7. The method of signaling which consists 100 in modulating a normal signaling band with a carrier so chosen as to produce a side band corresponding to the original signaling band and occupying a frequency range above the original signaling band, selecting said side band to the exclusion of other frequencies, combining with the selected band another normal signaling band, modulating the combined bands with a carrier so chosen as to 105 translate the combined bands to a point in the frequency spectrum higher than a third normal signaling band, selecting the frequencies thus translated to the exclusion of other frequencies, combining therewith said third normal signaling band.

8. The method of signaling which consists 110 in transmitting a band of frequencies corresponding to a signal but elevated in the frequency spectrum with respect to the normal 115 120 125 bands to be transmitted.

9. The method of signaling which consists 130 in transmitting a band of frequencies corresponding to a signal but elevated in the frequency spectrum with respect to the normal

- signaling range, transmitting with said band other signaling bands, stepping down said first mentioned band in the frequency spectrum by a plurality of steps until it is brought into the normal signaling range, and selecting one of the other bands into an individual circuit each time the first mentioned band is stepped down until all of the bands have been selected.
9. The method of signaling which consists in transmitting a frequency range comprising a plurality of sub-bands corresponding to as many signals, each comprising originally its given range but elevated in said frequency range above its normal range, stepping the frequency range down in the frequency spectrum until one of the sub-bands is brought into its normal signaling range and selecting this sub-band in its normal range to the exclusion of the other sub-bands.
10. A method of signaling which consists in transmitting a frequency range comprising a plurality of sub-bands, stepping down the range of frequencies in the frequency spectrum until one of the sub-bands is brought within a desired normal range, selecting the latter sub-band in its normal range to the exclusion of the other sub-bands, stepping down the remaining sub-bands to a point in the frequency spectrum such that another of the bands is brought into its normal range, and selecting the latter band.
11. The method of signaling which consists in transmitting a frequency range comprising a plurality of sub-bands, stepping down the range of frequencies in the frequency spectrum until one of the sub-bands is brought within a desired normal range, selecting the latter sub-band in its normal range to the exclusion of the other sub-bands, stepping down the remaining sub-bands to a point in the frequency spectrum such that another of the bands is brought into its normal range, selecting the latter band and continuing the process of stepping down and selecting individual bands until all of the bands have been selected.
12. The method of signaling which consists in transmitting a range of frequencies comprising a plurality of sub-bands, selecting one of the sub-bands, stepping the remaining sub-bands down to a point in the frequency spectrum such that one of them is brought within a desired normal range, and selecting the latter band in its normal range to the exclusion of the remaining bands.
13. The method of signaling which consists in transmitting a range of frequencies comprising a plurality of sub-bands, selecting one of the sub-bands, stepping down the remaining sub-bands in the frequency spectrum to a point such that one of said sub-bands is brought into a desired normal range, selecting the latter sub-band in its normal range to the exclusion of the remaining sub-bands, stepping down the remaining sub-bands to a point in the frequency spectrum such that still another band is brought into its normal range, and selecting the latter band.
14. The method of signaling which consists in transmitting a range of frequencies comprising a plurality of sub-bands, selecting one of the sub-bands, stepping down the remaining sub-bands in the frequency spectrum to a point such that one of said sub-bands is brought into a desired normal range, selecting the latter sub-bands in its normal range to the exclusion of the remaining sub-bands, stepping down the remaining sub-bands to a point in the frequency spectrum such that still another band is brought into its normal range, selecting the latter band, and continuing the process of stepping down and selecting until all of the bands have been selected.
15. The method of signaling which consists in transmitting a range of frequencies comprising a plurality of sub-bands, modulating the range of frequencies with a carrier so chosen as to bring one of the sub-bands to a point in the frequency spectrum within a desired normal range, and selecting the latter sub-band in its normal range to the exclusion of the remaining sub-bands.
16. The method of signaling which consists in transmitting a range of frequencies comprising a plurality of sub-bands, modulating the said range of frequencies with a carrier frequency so chosen as to translate the range of frequencies to a point in the frequency spectrum such that one of the sub-bands is brought into a desired normal range, selecting the latter sub-band in its normal range to the exclusion of the remaining sub-bands, modulating the remaining sub-bands with a carrier so chosen as to translate them to a point in the frequency spectrum such that one of the remaining sub-bands will be brought into its normal range, and selecting the latter sub-band.
17. The method of signaling which consists in transmitting a range of frequencies comprising a plurality of sub-bands, modulating the said range of frequencies with a carrier frequency so chosen as to translate the range of frequencies to a point in the frequency spectrum such that one of the sub-bands is brought into a desired normal range, selecting the latter sub-band in its normal range to the exclusion of the remaining sub-bands, modulating the remaining sub-bands with a carrier frequency so chosen as to translate them to a point in the frequency spectrum such that one of the remaining sub-bands will be brought into its normal range, selecting the latter sub-band,

and continuing the process of modulating and selecting bands until all of the bands have been selected.

18. The method of signaling which consists in transmitting a plurality of sub-bands arranged one above the other in the frequency spectrum, successively stepping down the sub-bands in the frequency spectrum simultaneously, and selecting one of the stepped-down bands for each step.

19. The method of signaling which consists in transmitting a plurality of sub-bands arranged one above the other in the frequency spectrum, simultaneously stepping down of the bands by successive steps so as to bring one of the bands at a time into a desired normal range, and selecting the band brought into its normal range from the remaining bands after each operation of stepping down.

20. In a signaling system, a plurality of signaling channels each including means to provide a range of signaling frequencies, means to successively step up a range of frequencies from one of said signaling channels, and means to successively add ranges of frequencies from the other signaling channels for each stepping-up operation.

21. In a signaling system, a plurality of signaling channels each including means to provide a range of signaling frequencies, means to successively step up a range of frequencies from one of said signaling channels, and means to add successively ranges of frequencies from the other signaling channels for each stepping-up operation so that the added frequencies may be stepped up simultaneously as they are added.

22. In a signaling system, a plurality of signaling channels each including means to provide a range of signaling frequencies, means to step up a band of frequencies from one of said signaling channels, means to combine with the stepped-up band a band of frequencies from another signaling channel, means to step up both bands together, and means to combine therewith a band from a third signaling channel.

23. In a signaling system, a plurality of signaling channels each including means to provide a range of signaling frequencies, means to step up a band of frequencies from one of said signaling channels, means to combine with the stepped-up band a band of frequencies from another signaling channel, means to step up both bands together, means to combine therewith a band from a third signaling channel, and means to successively step up the combined bands and add additional bands from other channels until the bands from all of the channels have been added.

24. In a signaling system, a plurality of signaling channels each including means to

provide a range of signaling frequencies, means to modulate a band of frequencies from one of said signaling channels by a carrier so chosen as to step the band up in the frequency spectrum, means to combine with the stepped-up band a band from another signaling channel, means to modulate the combined bands with a carrier frequency so chosen as to step up the combined bands in the frequency spectrum, and means to combine with the stepped-up bands a band from still another signaling channel.

25. In a signaling system, a plurality of signaling channels each including means to provide a range of signaling frequencies, means to modulate a band of frequencies from one of said signaling channels by a carrier so chosen as to step the band up in the frequency spectrum, means to combine with the stepped-up band a band from another signaling channel, means to modulate the combined bands with a carrier frequency so chosen as to step up the combined bands in the frequency spectrum, means to combine with the stepped-up bands a band from still another signaling channel, and means to successively step up the combined bands by modulating with carrier frequencies and adding bands from other signaling channels until the bands of all of the signaling channels have been added.

26. In a signaling system, a main transmission circuit and a plurality of signaling channels, means to transmit a signaling band from said main transmission circuit together with other signaling bands, means to successively step down said first mentioned signaling band in the frequency spectrum until it is brought into a desired normal range, and means to select one of the other signaling bands into one of said signaling channels for each stepping down operation until all of the bands have been selected into the signaling channels.

27. In a signaling system, a main transmission circuit and a plurality of signaling channels, means to transmit over said main transmission circuit a range of frequencies comprising a plurality of sub-bands, means to step down said range of frequencies to a point in the frequency spectrum such that one of the sub-bands is brought into a desired normal range, means to select the latter band into one of said signaling channels, means to step down the remaining bands to a point such that one of them is brought into its normal range, and means to select the latter band into another signaling channel.

28. In a signaling system, a main transmission circuit and a plurality of signaling channels, means to transmit over said main transmission circuit a range of frequencies comprising a plurality of sub-bands, means

to step down said range of frequencies to a point in the frequency spectrum such that one of the sub-bands is brought into a desired normal range, means to select the latter band into one of said signaling channels, means to step down the remaining bands to a point such that one of them is brought into its normal range, means to select the latter band into another signaling channel, and means to continue the process of stepping down and selecting bands until all of the bands have been selected into their signaling channels.

29. In a signaling system, a main transmission circuit and a plurality of signaling circuits, means to transmit a range of frequencies over said main transmission circuit including a plurality of signaling bands, one of which is in its normal signaling range, means to select the latter signaling band into one of said signaling channels, means to step down the remaining signaling bands until one of them is brought into its normal signaling range, means to select the latter signaling band into another signaling channel, means to step down the unselected sub-bands until another band is brought within its normal signaling range, means to select the latter signaling band into a third signaling channel, and means to successively step down the remaining bands and to select the bands brought into their normal signaling range until all of the bands have been selected into their signaling channels.

and means to select the latter sub-band into a third signaling channel. 30

30. In a signaling system, a main transmission circuit and a plurality of signaling circuits, means to transmit a range of frequencies over said main transmission circuit including a plurality of signaling bands, one of which is in its normal signaling range, means to select the latter signaling band into one of said signaling channels, means to step down the remaining signaling bands until one of them is brought into its normal signaling range, means to select the latter signaling band into another signaling channel, means to step down the unselected sub-bands until another band is brought within its normal signaling range, means to select the latter sub-band into a third signaling channel, and means to successively step down the remaining bands and to select the bands brought into their normal signaling range 35 until all of the bands have been selected into their signaling channels. 40

In testimony whereof, I have signed my name to this specification this 30th day of June, 1921.

LLOYD ESPENSCHIED.
